(57) **CLAIM**

The ornamental design for wine rack, as shown and described.

DESCRIPTION

FIG. 1 is a top front, left side perspective view of a wine rack showing my new design.

FIG. 2 is a front perspective view thereof.

FIG. 3 is a front view thereof, the rear view being a mirror image.

FIG. 4 is a right side view thereof.

FIG. 5 is a top plan view thereof; and,

FIG. 6 is a bottom plan view thereof.

My wine rack is characterized by having the shape of a large wine glass.
